(57) **CLAIM**

The ornamental design for an automobile body front fascia, as shown and described.

DESCRIPTION

FIG. 1 is a right perspective view of an automobile body front fascia showing our new design;

FIG. 2 is a front view;

FIG. 3 is a right side view; and,

FIG. 4 is a left side view thereof.

The broken line showing an automobile is for the purpose of illustrating environmental structure and portions of the front fascia that forms no part of the claimed design.
